UNITED STATES PATENT OFFICE

2,422,263

TILTABLE TRAP CHAMBER POWDER
DISPENSING DEVICE

Earl M. Schara, Washington, D. C.

Application October 19, 1944, Serial No. 559,442

6 Claims. (Cl. 222—126)

1

This invention relates to dispensing receptacles or containers and more particularly to containers for tooth powder or the like having means for the insertion of a brush and means for discharging upon the brush the desired quantity of material without waste.

The general object of the invention is the provision of a novel and improved dispensing device of this type which is of simple and sturdy construction, having no valves, gates, or other moving parts to manipulate or be liable to get out of order.

It is an object of the invention to provide a dispensing container for material of the nature described, which comprises a storage compartment and an auxiliary dispensing compartment disposed alongside of the storage compartment, means being provided for the insertion of a brush into the auxiliary compartment, and openings leading from the storage compartment to the auxiliary compartment through which a predetermined quantity of material may pass from the storage compartment to the auxiliary compartment at the lower part thereof and then shower down upon the brush when the container is inverted.

In the preferred embodiment, the invention contemplates the provision of a box or container having a main compartment adapted to contain the bulk of the powder and an auxiliary compartment separated from the main compartment by a partition of novel construction and function, the auxiliary compartment generally being the smaller of the two and adapted to receive the brush to which the powder is to be applied. This compartment is preferably widest at its mid-portion where the brush is inserted and is narrowed toward its upper and lower ends by the inclination of the partition at those points. The inclined or overhanging portions of the partition are provided with openings through which some powder may pass into the auxiliary compartment. Then when the container is inverted this small quantity of powder showers down upon the brush positioned in the mid-portion of the compartment, any excess falling to the bottom of the compartment from whence it may either be returned to the main compartment by a tilting of the container or it may again be dropped upon the brush upon the inversion of the container.

Among the more specific objects of the invention are the provision of a dispensing container of this character in which the auxiliary compartment is provided with its own side walls as well as the beforementioned partition which com-

2

prises its end wall; one in which a simple partition is provided, the outer walls of the container comprising the side walls of the auxiliary compartment; and one in which the auxiliary compartment is disposed upon the side of the container remote from the opening through which the brush is introduced, whereby the possibility of loss of powder from the container is further diminished.

10 Within the scope and intent of the invention, the novel receptacle may be comprised by the original package as packed at the factory and sold to the trade, or it may be a relatively permanent dispensing receptacle to be filled and refilled by the user from a bulk supply of powder.

Other objects of the invention, including the provision of means for supporting the brush from the container when it is not in use, will be understood from the following specification when read in connection with the accompanying drawings in which certain embodiments of the invention are illustrated by way of example.

In the drawings:

Figure 1 is a view in vertical section of a dispensing container embodying the principles of the invention;

Figure 2 is a view partly in plan and partly in horizontal section of the container, taken on line 2—2 of Figure 1;

Figure 3 is a view in end elevation of the same container;

Figure 4 is a view partly in side elevation and partly in vertical section of a modified form of the container;

Figure 5 is a fragmentary horizontal section taken on line 5—5 of Figure 4;

Figure 6 is a vertical sectional view of still another embodiment of the invention; and

Figure 7 is a horizontal central sectional view of the container shown in Figure 6.

Referring now more particularly to Figures 1 to 3 inclusive of the drawings, it will be seen that the container indicated generally by the reference

45 numeral 10 in these figures comprises a main body portion 11 which may be rectangular in vertical section and either rectangular or oval shaped in horizontal section, and upper and lower closures 12 and 13 which are provided with rims or flanges 14 which embrace the margins of the body portion 11. The container may be made of any suitable material such as sheet metal, pasteboard, or plastic; and the top and bottom closures 12 and 13 may be either removable or permanently se-

50 cured in place upon the body portion 11 after the

container is filled with the tooth powder or other material.

In this embodiment of the invention a storage compartment 15 is provided at one side of the container and an auxiliary dispensing compartment 16 at the opposite side. The compartment 16, in this case, is formed by the triple partition member 18 which may be formed of the same material as the parts 11, 12, and 13. The member 18 comprises an end wall 19 having a central vertical portion 20 and upper and lower inclined portions 21 and 22. The member 18 also includes the side wall portions 24 and 25 which are secured as at 26 and 27 to the inner walls of the body portion 11 of the container adjacent one end thereof.

The extreme upper and lower portions of the inclined walls 21 and 22 of the partition 19 are slotted as at 30 to a predetermined depth to provide communication between the storage compartment 15 and the upper and lower ends of the auxiliary compartment 16. Directly opposite the central vertical wall portion 20 of the partitioned wall 19 there is formed an opening 33 in the outer wall of the member 11 through which the tooth brush 40 may be introduced. This opening 33 may be sealed at the factory by a readily removable patch 34 or other closure so as to prevent loss of any of the contents of the container.

The operation of the device will be readily understood. With the container in the position shown in Figure 1 of the drawings, a small regulated quantity of powder will fall through the lowermost slot 30 into the then lower portion of the auxiliary or dispensing compartment 16. The brush is inserted in the opening 33 and then the container 10 is inverted so that the previously lower portion of the compartment 16 becomes the upper portion so that the powder therein falls downwardly upon the bristles of the brush 40, any excess falling to the new bottom portion of the compartment to mingle with any of the powder passing through the lower opening 30 from the storage compartment 15. The brush may be inserted with the bristles directed downwardly and inverted with the container, or preferably it may be inserted with the bristles upward and the container rotated about the brush to inverted position.

In Figures 4 and 5 of the drawings, a modified form of the invention is shown in which there is provided a single inner partition 19' which extends from one side to the other of the body portion 11 of the container and divides the container into the two compartments 15' and 16'. In this case, the side walls of the compartment 16' are identical with the side walls of the container body portion 11, the side edges of the partition 19' being secured as at 26' and 27' to the inner surfaces of the wall portion 11. The upper and lower ends of the partition 19' are provided with the slots and notches 30' which perform the same functions as the openings 30 in the previously described embodiment.

The form of the invention shown in Figures 4 and 5 is of a somewhat simpler and less expensive construction and the operation is exactly the same as in the case of the one previously described.

In Figures 6 and 7 of the drawings there is shown a further modification of the device in which the dispensing compartment 16'' is disposed in the side of the storage compartment 15'', which is remote from the opening 33''. The compartment 16'' is substantially frusto-pyramidal in shape having the side and end walls 19''. Connecting the opening 33'' with the dispensing com-

partment 16'' is the tubular passageway 35 having the walls 36 and preferably being of rectangular configuration. The upper and lower walls 19'' are provided with the openings 30'' through which the powder passes into the compartment 16'' and falls upon the brush which is in this case inserted through the opening 33'' and the passageway 35 into the dispensing compartment 16''.

In Figures 1, 2 and 4 of the drawings, there is illustrated one feature of the invention whereby there is provided supporting means for the brush 40 when it is not being used. The upper surface of the cover 12 is extended beyond the confines of the body portion 11 as at 50 and is provided with an opening 51 having a narrower slot 52 communicating therewith. The slot 52 is of a width greater than the thickness of the neck portion 45 of the brush but smaller than the width thereof. The width of the opening 51 is also smaller than the upper bristle carrying part 46 of the brush. This arrangement provides means whereby the brush may be inserted edgewise through the slot 52 and then rotated to a sidewise position in the opening 50 and thus supported in the position indicated in Figure 1 of the drawings.

It is understood that the expressions, "top," "bottom," "upper," "lower," "side," and similar directional terms as used in certain of the claims, are merely relative, and are descriptive of the invention not only as illustrated in the drawings accompanying the present application, but also of the same or similar devices which are normally adapted to be disposed so as to rest upon any of its surfaces. Thus, for example, the dispensing container illustrated in Figs. 6 and 7 of the drawings, when provided with suitable sealing closures, such as that shown at 34 in Fig. 3, might well normally rest upon its right-hand side. Similarly, the device might be disposed upon its left-hand side and the containers illustrated in the other figures of drawings disposed in normal idle position upon any of their surfaces.

Also, it is hardly necessary to add that in the described operation of the device, the lower portion becomes the upper portion upon inversion of the container and the upper portion becomes the lower portion, and this terminology will be clearly understood in the claims.

It is also obvious that a sticker closure such as is designated at 34 may be applied to the opening 33' in Fig. 4.

Various changes and modifications may be made in the embodiments illustrated and described herein without departing from the scope of the invention as defined by the following claims.

Having thus described the invention, what is claimed as new and desired to be secured by Letters Patent is:

1. An invertible dispensing container for tooth powder or like material, which comprises in combination a storage compartment and an auxiliary compartment alongside said storage compartment, an opening through the container wall into said auxiliary compartment at a point intermediate the upper and lower ends thereof for the insertion of a brush or like instrumentality, and relatively small openings leading from said storage compartment into the upper and lower ends respectively of said auxiliary compartment, the opening at the then lower end providing access for a limited amount of material into the then bottom portion of the auxiliary compartment, which material will shower down upon said inserted instrumentality upon inversion of the container.

tainer, and another supply of material will issue from said storage compartment into the new bottom portion of the auxiliary compartment, which was the original top portion thereof prior to inversion, preparatory to a repetition of the inverting and dispensing process.

2. An invertible dispensing container for tooth powder or like material, which container is substantially symmetrical about a horizontal central plane, and has a storage compartment and an auxiliary dispensing compartment arranged side by side, an opening through the container wall into said auxiliary compartment at approximately the mid-point of the vertical length of the container for the insertion of a brush or like instrumentality, and relatively small openings leading from said storage compartment into the upper and lower ends respectively of said auxiliary compartment, the opening at the then lower end providing access for a limited amount of material into the then bottom portion of the auxiliary compartment, which material will shower down upon said inserted instrumentality upon inversion of the container, and another supply of material will issue from said storage compartment into the new bottom portion of the auxiliary compartment, which was the original top portion thereof prior to inversion, preparatory to a repetition of the inverting and dispensing process.

3. An invertible dispensing container for tooth powder or like material which container is substantially symmetrical about a horizontal central plane and is provided with a generally vertically disposed partition dividing said container into two compartments, one a storage compartment for said material and the other an auxiliary dispensing compartment, said partition being inclined toward the auxiliary compartment side of the container at its upper and lower portions, thus assuming a wide approximately U-shaped configuration when turned on its side, said compartments having common top and bottom walls, notches formed in the upper and lower ends of said partition and providing openings affording access for a limited amount of material into the then bottom portion of the auxiliary compartment, which material will shower down upon said inserted instrumentality upon inversion of the container, and another supply of material will issue from said storage compartment into the new bottom portion of the auxiliary compartment, which was the original top portion thereof prior to inversion, preparatory to a repetition of the inverting and dispensing process.

4. The container as set forth in claim 2 in which the auxiliary compartment is disposed upon the side of the container remote from the brush opening, and a passageway connecting the opening with the auxiliary compartment passes through the storage compartment.

5. A dispensing container for tooth powder or like material, which comprises a lightweight, readily portable, merchantable package, having

top, bottom, and side walls and provided with a generally vertically disposed partition extending from the top wall of the container to the bottom wall thereof and dividing the container into two compartments of substantially the same height arranged side by side, one comprising a storage compartment and the other an auxiliary, dispensing compartment, an opening in the wall of said auxiliary compartment which is on the opposite side thereof from said partition, said opening being spaced from both the top and bottom of said container, and adapted for the insertion of a toothbrush or similar instrumentality laterally into the compartment toward said partition, and a small dispensing opening in the partition adjacent its lower end, through which a limited quantity of said powder may flow into the then bottom portion of the auxiliary compartment, so that said quantity will shower down upon said inserted instrumentality upon inversion of the container.

6. A dispensing container for tooth powder or like material, which comprises a lightweight, readily portable, merchantable package, provided with a generally vertically disposed partition dividing the container into two compartments arranged side by side, one comprising a storage compartment and the other an auxiliary, dispensing compartment, an opening in the wall of said auxiliary compartment which is on the opposite side thereof from said partition, said opening being spaced from both the top and bottom of said container, and adapted for the insertion in inverted position, of a toothbrush or similar instrumentality laterally into the compartment toward said partition, said partition being inclined downwardly and laterally toward the auxiliary compartment from a point opposite the opening to the lower end of the partition, and a small dispensing opening in the inclined part of the partition adjacent said lower end, through which a limited quantity of said powder may flow into the then bottom portion of the auxiliary compartment, so that said quantity will shower down upon said inserted instrumentality upon inversion of the container, the inclination of the partition permitting the insertion of the end of the instrumentality within the container laterally beyond the dispensing opening.
